Attest,

UNITED STATES PATENT OFFICE.

CHARLES A. HEIM, OF BROWNSVILLE, INDIANA.

LACING-LOOP.

No. 877,564.

Specification of Letters Patent.

Patented Jan. 28, 1908.

Application filed March 21, 1907. Serial No. 363,730.

To all whom it may concern:

Be it known that I, CHARLES A. HEIM, a citizen of the United States, residing at Brownsville, Indiana, have invented a new and useful Improvement in Lacing-Loops, of which the following is a specification.

My invention relates to lacing loops of the class adapted to the use of shoes or other articles and the objects of my improvement are to provide means for maintaining the quarters in closely fitting contact with the counter and tongue for excluding water or dust, to provide means adapted to engage with the lace for preventing excessive wrinkling of the counter and for maintaining it in proper position in relation to the quarters; to provide means for maintaining the lace entirely on one side of the member to which it is attached, and to provide a cheap and durable device which is efficient and will not injure the lacings. These objects and others are attained in the following described manner as illustrated in the accompanying drawings in which,—

Figure 1 is a front view of a shoe embodying my improvements; Fig. 2, a longitudinal section, Fig. 3 a plan, Fig. 4 a side elevation, Fig. 5 an inverted plan and Fig. 6 a front elevation of my improved lacing loop; Fig. 7 shows the prongs in clenched position on the under surface of the leather; Fig. 8 the front elevation of a holder provided with but one front clenching prong.

In the drawings, 1 represents the counter of an ordinary shoe, 2 the tongue, 3 the quarters, 4 the lacing hooks and 5 the lace or shoe string. Lacing loops 6 which may be substituted for the ordinary eyelets for engaging the shoestring are positioned entirely on the outer surface of the quarters. One of said loops may be attached to the outer surface of the counter as shown in Fig. 1, for engaging the middle portion of the lace. Said loops or eyes each consist of a triangular shaped piece of sheet metal which is formed with similar pointed clenching prongs or tangs 11 and 13 extending in the same direction respectively from its apex and the extremities of its base portion 8. The bridge or middle portion is curved longitudinally to form an interiorly concave bearing 7, and the base portion is curved laterally to form an interiorly convex bearing 12 for the sliding engagement therewith of the lacing or shoe string 5. Said tangs 13 may be substituted by a single tang 14 which depends from the

middle portion of wall 8 if desired, as shown in Fig. 8. Said loops or staple eyes may be secured to the outer surface of the leather by inserting the tangs therethrough and clenching them on the opposite side as shown in Figs. 4 and 7. The shoestring 5 may be inserted through the eye holes in movable contact with the bearings 12 for lacing the adjacent quarters together and in closely fitting contact with the tongue and counter.

One of the loops may be secured on the counter just below the quarters and in the line of their separation as shown at 17 in Fig. 1 for engaging with the middle portion of lace 5 whereby the counter and quarters are yieldingly connected together and the tendency on the part of either to excessive wrinkling is materially obviated. It is desirable that the lace should not be entirely disengaged from the quarters for the removal of the shoe and the use of hooks 4 are therefore confined to the upper portion of the quarters. In the use of ordinary eyelets and the usual round or leather shoe strings as is used in heavy shoes by workingmen the portion of the strings between the quarters and the tongue form permanent creases in the tongue which injure the instep of the wearer. They also separate the quarters from the tongue sufficiently to admit the passage of dust or water to the interior of the shoe. By placing the shoe strings entirely on the outside, the quarters are held in close contact with the tongue and with the counter for excluding dust or water and the objectional creases in the tongue are entirely obviated.

It is evident that different means may be employed for attaching a horizontal eye to the shoe. I do not therefore confine myself to the specific manner shown, and described but

What I claim as my invention and desire to secure by Letters Patent of the United States is:—

1. As a new article of manufacture, a lacing loop consisting of a triangular shaped piece of sheet metal formed with a longitudinal curve and with similar pointed clenching tangs projecting respectively from its apex and from said base portion in a direction parallel with each other.

2. As a new article of manufacture, a lacing loop consisting of a triangular shaped piece of sheet metal formed at its corners with sharp clenching prongs, and having its body portion formed with a longitudinal bend

and also with a lateral bend to form an interiorly convex wall, said prongs being extended in the same direction parallel with each other.

3. As a new article of manufacture, an open 5 loop consisting of a triangular shaped piece of sheet metal terminating at its corners in clenching prongs and having its base portion curved laterally and its bridge portion curved longitudinally said clenching prongs being 10 extended in the same direction parallel with each other.

4. As a new article of manufacture, a lacing loop consisting of a triangular shaped piece of metal formed with a longitudinal bend and with an interiorly convex wall by a 15 lateral bend of its base portion, and provided with clenching prongs projecting in the same direction perpendicular to a common plane.

CHARLES A. HEIM.
